UNITED STATES PATENT OFFICE.

FRANK MÜLLER, OF NEW YORK, N. Y., ASSIGNOR TO FRIEDERICA BUCH-MÜLLER, OF SAME PLACE.

FOOT-REST FOR BOOT-BLACKING STANDS.

SPECIFICATION forming part of Letters Patent No. 610,363, dated September 6, 1898.

Application filed July 27, 1897. Serial No. 646,126. (No model.)

To all whom it may concern:

Be it known that I, FRANK MÜLLER, a citizen of Switzerland, residing at New York, (Brooklyn,) in the county of Kings and State 5 of New York, have invented certain new and useful Improvements in Foot-Rests for Boot-Blackening Stands, of which the following is a specification.

This invention relates to an improved foot-10 rest for boot-blacking stands; and its object is to provide such a foot-rest with independently-adjustable clamps to hold the foot firmly in position while the shoe is being polished.

15 The invention consists of a foot-rest provided with independently-adjustable clamps, substantially as herein shown and described.

The invention consists, further, of details of construction hereinafter described, and defined in the claims.

20 Referring to the drawings, Figure 1 is an elevation of my improved foot-rest in operative position. Fig. 2 is a top view thereof. Fig. 3 is an elevation of the same, one half of 25 the foot-rest being removed, showing the arrangement of the clamps and their operating-lever. Fig. 4 is a vertical section on the line 4 4 of Fig. 3. Figs. 5 and 6 are top and side views of the toe-clamps. Figs. 7 and 8 are 30 side and edge views of the lever. Fig. 9 is a side view of the heel-clamp. Fig. 10 is a view similar to Fig. 3, showing a modification. Fig. 11 is a front elevation, parts being in section, on line x x of Fig. 10. Fig. 12 is a top view 35 of the top or cover, and Fig. 13 is a detail.

In the drawings, A represents a foot-rest 40 adapted to be secured upon a boot-blacking stand, and is preferably made of a metal base or standard cast in suitable shape for the purpose. For convenience the base of the foot-rest may be cast in two parts a a', which are secured together by means of suitable rivets. The top or cover B is made separate and is riveted in position upon the base of 45 the foot-rest and is shaped to conform with the outline of a shoe, as is usual in such constructions. Each part a a' of the base of the foot-rest A is shaped to the form of a shoe at the top, and is provided at the heel portion 50 with lugs a² and at the toe portion with orifices a³, by means of which the cover B is firmly riveted in place. The heel portion is also cut away at a⁴ to accommodate the heel

portion of the cover B. At the heel portion is formed a channel a⁵, and at the outside of the toe portion is a similar channel a⁶, which channels form ways or guides for the toe and heel clamps. At the toe portion is provided a recess, which when the two halves of the foot-rest are secured together forms a slot a⁷, 60 through which the handle of the operating-lever passes, as will be hereinafter described. One side of this slot a⁷ is notched, as at a⁸, for the purpose of locking the lever when the shoe is clamped to the foot-rest. Each part a a' of the base of the foot-rest A is provided with a ledge H H', upon which the fulcrum-pins g³ of the lever rest.

Through the channels a⁶ a⁶ are guided two toe-clamps D D, which are formed of angular 70 strips of metal having upturned end portions d d for pressing against the sole of the shoe. The rear end of each toe-clamp D is provided with a depending flange d', having a perforation d² formed therein. The extremity of 75 each toe-clamp D is curved on the inside at d³, as shown in Fig. 5. The heel-clamp E is formed of a metal strip having an upturned end portion e for clasping the heel of the shoe. The rear end of the heel-clamp E is 80 provided with a depending flange e', having a perforation e².

The lever G is provided with a curved handle g and a T-shaped head g'. At the upper extremity of the head g' are provided two 85 lugs g² g², which extend transversely from said head, one on each side thereof. Near the center of the head g' are arranged two lugs g³ g³ below the lugs g² g² and similarly 90 arranged, which serve as fulcrums upon which the lever operates. The head g' of the lever is cut away on one side below the fulcrum-lugs and near the lower end thereof is provided a lug g⁴, which extends transversely 95 from said head. The shank of the lever G is provided with a sharp edge to engage with the teeth a⁸ formed on one side of the slot a⁷ of the foot-rest.

Upon the inside of each part a a' of the base of the foot-rest and near the center 100 thereof is formed a ledge H H', which serve as supports for the fulcrum-lugs g³ g³. These ledges H H' are of considerable length and afford space for the fulcrum-lugs g³ g³ to move 105 during the operation of clamping the shoe to the stand. This play of the fulcrum-lugs

upon the ledges H H' permits the independent adjustment of the toe and heel clamps to any length or width of shoe. When the shoe is short and broad, the toe-clamps bind first 5 the fulcrum-lugs, then slide along the ledges H H' and permit the adjustment of the heel-clamp. When the shoe is long and narrow, the heel-clamp engages first and the fulcrum-lugs move along the ledges H H', drawing the 10 toe-clamps against the shoe. It will thus be seen that the fulcrum shifts in clamping shoes of different sizes from the lugs g^3 g^3 to the lug g^4 or the lugs g^2 g^2 , in accordance with the 15 size and shape of the shoe.

15 The cover B is provided with suitable lugs and openings, by which it is riveted to the base of the foot-rest, and has upon its under surface and near the middle portion two 20 guide-lugs b b', which serve to steady and 25 guide the toe-clamps D D in their movements when operated by the lever G.

The parts are assembled by passing the handle of the lever down into the foot-rest and through the slot a^7 . The fulcrum-lugs g^3 g^3 25 rest upon the ledges H H'. The heel-clamp is then attached to the lug g^4 and the two toe-clamps D D are attached to the lugs g^2 g^2 . The cover B is then applied and riveted in place, when the device is ready for use. When 30 the foot is placed upon the foot-rest, the operator simply moves the lever in an upward direction as far as it will go, which movement causes the clamps to travel inwardly and clamp the heel and sole of the shoe firmly 35 to the foot-rest. The lever is locked in this position by engaging with the teeth a^8 of the slot a^7 , thus holding the shoe firmly in place while being operated upon.

In Figs. 10, 11, and 13 is shown a modified 40 form whereby the lever G may be positively locked when the shoe is clamped in position on the stand. In the form shown in said figures both sides of the slot a^7 are notched or serrated, as at a^8 . The lever G is provided 45 upon its under side with flanges f, which serve as guideways for the locking-key F, which is provided with lugs f', whereby it is secured to and adapted to slide upon the guideways f. The locking-key F is provided at one end 50 with a finger-hold f², while the other end terminates in a beveled or triangular point f³, whose sides are adapted to engage the notches or serrations a^8 of the slot a^7 . The operation 55 of the modification will be readily understood from the above description. When it is desired to clamp a shoe to the foot-rest, the lever G is grasped and a finger inserted in the finger-hold f², the locking-key is retracted, and the lever released. When the lever is 60 forced upwardly as far as it will go in clamping the shoe, the locking-key is moved along the guideways until it engages the serrations a^8 and locks the clamping mechanism.

Having thus described my invention, I 65 claim as new and desire to secure by Letters Patent—

1. In a foot-rest for boot-blacking stands,

the combination, with toe and heel clamps, of a pivotal operating-lever therefor having a shiftable fulcrum, and suitable supports on 70 which said fulcrum moves, substantially as set forth.

2. In a foot-rest for boot-blacking stands, the combination with a base having fulcrum- 75 ledges, of a lever provided with fulcrum-lugs mounted upon said ledges, and toe and heel clamps connected with said lever and adapted to be operated thereby, substantially as set forth.

3. In a foot-rest for boot-blacking stands, 80 the combination with the base provided with fulcrum-ledges, of a lever having a T-shaped head, pivot-pins on said head, toe and heel clamps connected to said pivot-pins, and fulcrum-lugs located between said pivot-pins 85 and adapted to rest upon said ledges, substantially as set forth.

4. In a foot-rest for boot-blacking stands, the combination with a base provided with a slot and fulcrum-ledges, of a lever having a 90 T-shaped head, and working through said slot, fulcrum-lugs carried by said lever and adapted to rest upon said ledges, pivot-pins upon either side of said lugs, toe-clamps connected with the upper pivot-pins, and a heel-clamp connected with the lower pivot-pin, 95 substantially as set forth.

5. In a foot-rest for boot-blacking stands, the combination with a base provided with a slot and fulcrum-ledges, of a foot-plate secured to said base, toe and heel clamps guided in ways beneath said foot-plate, a lever having a T-shaped head working through 100 said slot, pivot-pins at the upper portion of the T-shaped head, a pivot-pin at the lower 105 portion of said head, and operatively connected with said toe and heel clamps, and fulcrum-lugs located between said upper and lower pivot-pins and adapted to rest upon said fulcrum-ledges, substantially as set forth. 110

6. In a foot-rest for boot-blacking stands, the combination with the base provided with fulcrum-ledges, of a lever provided with fulcrum-lugs, mounted upon said ledges, toe and heel clamps connected with said lever and 115 adapted to be operated thereby and means for locking said lever, substantially as set forth.

7. In a foot-rest for boot-blacking stands, the combination with a base provided with a 120 slot having serrated sides, of a suitable clamping mechanism, a lever for operating said clamping mechanism extending through said slot, and a locking-key mounted upon said lever and adapted to engage with the serrated 125 slot of the base, substantially as set forth.

In testimony that I claim the foregoing as my invention I have signed my name in presence of two subscribing witnesses.

FRANK MÜLLER.
